CLAIM

The ornamental design for a skincare device as shown and described.

DESCRIPTION

FIG. 1 is a perspective view of a skincare device.

FIG. 2 is a front view of the skincare device.

FIG. 3 is a rear view of the skincare device.

FIG. 4 is a right side view of skincare device.

FIG. 5 is a left side view of the skincare device.

FIG. 6 is a top view of the skincare device; and,

FIG. 7 is a bottom view of the skincare device.

The broken lines shown in the drawings are for the purpose of illustrating portions of the skincare device, which form no part of the claimed design.
